UNITED STATES PATENT OFFICE.

FREDERICK E. HUDSON, OF ELLISBURG, NEW YORK.

SILO.

No. 851,091.

Specification of Letters Patent.

Patented April 23, 1907.

Application filed January 30, 1907. Serial No. 354,801.

To all whom it may concern:

Be it known that I, FREDERICK E. HUDSON, a citizen of the United States, residing at Ellisburg, in the county of Jefferson and State 5 of New York, have invented certain new and useful Improvements in Silos, of which the following is a specification.

This invention relates to improvements in silos, designed for use by farmers, dairymen 10 and others for the storing, curing and discharging of ensilage.

The object of the invention is to provide a stave silo, which is simple, strong and inexpensive, and wherein the construction and 15 arrangement of the tank is such that its interior is entirely free and clear of parts which may obstruct, and thereby interfere with the convenient handling, or the settling or compressing of the ensilage, which is essential to 20 the proper curing and preserving of the same.

A further object is to provide simple means comprising a series of closely fitting and readily detachable doors, for use in entering and discharging the silage, the said doors having 25 no connection with each other, and in equipping each door with simple but strong securing devices, as well as means for suspending and holding them, when open, in a safe and 30 convenient position ready for use when it is desired to close and fill the silo.

The invention further consists in novel means for effecting the splicing or joining of the ends of the staves which comprise the tank or body of the silo, and for binding and 35 holding the same when assembled.

Other features and parts of the invention will be fully understood from the detail description which follows, and by reference to the accompanying drawing forming a part of 40 this specification, and in which—

Figure 1 is an elevation and part section of my improved silo, showing the principal features and parts and the manner of constructing and arranging the same. Fig. 2 is a sectional view, substantially on the line 2—2 of Fig. 1, showing the close circular walls of the tank having an unobstructed and clear interior. Fig. 3 is a detail perspective view, showing one of the openings for the discharge 45 of the ensilage; also showing the novel manner in which the detachable door is suspended and held away from the opening by gravity.

Similar numerals of reference are assigned

to corresponding parts throughout the several views.

In the drawings, 2 represents the silo complete, which is preferably made of wood in the form of long narrow staves 3, which are matched and joined together to form a tight closure, circular in form, into which ensilage or other material for feeding cattle may be stored and preserved. The silo preferably rests upon a foundation, which may be made of any suitable material, but I prefer to employ concrete or rock, in the manner shown in the drawing.

Silos are generally built from twenty to forty feet in height, and from eight to sixteen feet in diameter, and to provide a strong and enduring structure of the class, the staves 3 are cut in different lengths, usually varying from six to twelve feet, and of any suitable width and thickness. In assembling the staves, they are applied in alternate courses 75 or layers so as to break joints. Where more than one stave is used in a course, the abutting ends are squared and then slotted and a steel or iron spline 4 is inserted in the slots, for the purpose of holding the staves rigidly 80 in place and preventing the warping of the ends and the opening of the joints by the action of the elements. When the circular wooden tank comprising the silo is completed, a suitable roof 5 is securely mounted 85 upon its top, and a filling door or window 6 is provided and disposed at a convenient point just above the upper end of the tank.

The silo may be constructed away from the site it is to occupy, and afterwards 90 mounted upon the foundation, but I prefer to build the tank right on the foundation, and then fill in concrete or like substance until the floor or bottom is raised two or three inches above the lower end of the tank. The 95 upper surface forming the floor of the silo should be covered with a heavy coating of cement and finished level and smooth. Under this construction, the bottom of the tank will be held securely in place and tightly 100 sealed, and the tank cannot become shifted upon its foundation.

In constructing my silo, the tank and all of the other parts, such as the roof, doors and floor are joined in a manner which will make 105 the whole practically air-tight and watertight, such condition being essential for the proper curing of the silage.

7, 7 represents a series of metallic hoops or bands, preferably round steel or iron, which surround the tank and are disposed in pairs at regular intervals, as shown in Fig. 1. 5 These bands are provided with adjustable draw-lugs 9 adapted to receive the threaded ends of the hoops, and with suitable nuts 10 which are employed for drawing and holding the hoops taut.

10 A series of openings 11 are cut in one side of the silo, preferably arranged one above the other, as shown. These openings should be disposed at equal distances from each other, the lowermost one extending to within 15 about one foot of the bottom of the silo, and the uppermost one ending about the same distance from the top of the tank. The openings 11 should be large enough for a man to enter readily and to discharge the ensilage, and through the same by the use of a fork or shovel. As hinged doors could not be relied upon to make an air-tight seal of the discharge openings during the period in which the silage is being cured, I have provided a 20 series of detachable doors 12, 12, which are made to tightly fit and close the openings 11, and they are preferably formed by cutting out a section of the tank-wall, four or five staves in width, and about two and one-half 25 feet in length. These doors are usually cut out after the staves have been joined and bound together, and in doing so, the upper ends are beveled upwardly and inwardly. Then the lower ends are cut parallel to the 30 upper ends, which gives the bevel at the lower end of the door a downward and outward slant, as shown in Fig. 3. The side edges of each door are also beveled inwardly, so that the inner face of the door is narrower 35 than the outer face. The employment of these latter features render it possible to make the doors air-tight.

40 13 represents a metallic part in the nature of a double hasp, which is securely bolted to the lower part of each door, and having perforated ends which extend several inches beyond the sides or edges of the door.

45 14, 14 represent studs or bolts which are driven through the tank wall on each side of the openings 11, and having their projecting outer ends threaded. These studs are disposed so that they register with the perforations 15 of the hasp 13. When the doors are placed in the openings 11 and the hasps 50 slipped over the studs 14, handle-nuts 16 are applied, and when the latter are screwed up tight, they draw or force the doors into the openings until all of the joints around them are air-tight.

55 60 The upper ends of the doors are held in place and flush with the inner and outer surfaces of the tank by the inwardly sloping bevels at the top and sides, the lower ends are bound and held by the hasps and handle-nuts, and when once secured in place in the

65 manner described, the doors will remain in that position and withstand the heavy pressure from the ensilage within, until the handle-nuts are removed and the lower ends made free.

70 In order to brace and hold together the upper ends of the staves comprising the doors, I provide a part 17, similar in form to that of the hasps 13, except that the ends do not project beyond the sides of the doors. This part 75 is also securely bolted to the doors. The parts 13 and 17 are each provided with a looped handle 19 for use in inserting and removing the doors.

80 The doors of the silo must necessarily be of the same thickness and weight proportionately as the walls of the tank, in order to fit and fill the openings 11, and also to stand the great strain exerted by the compressed silage, and when made large enough to be 85 serviceable they are too heavy for one person to handle without some means to assist in opening and closing them. To that end I have provided a stout chain, or like flexible part 20, one end of which is attached to the 90 door near its upper end, the other end being secured to the wall of the tank at a point which will allow the door, when released, to gravitate away from and hang clear of the opening, as shown in Fig. 3.

95 To enable a person to reach the doors which are disposed one above the other, I have provided a simple ladder, extending from the bottom to the top of the silo, and consisting of a series of metallic or wooden rounds or cleats 21, which are bolted or otherwise suitably secured to the outside of the tank.

100 The silos are generally filled with ensilage in the fall of the year by passing it through 105 the filling window 6, and after it ferments and becomes cured, it is then fed to the cattle. When the feeding begins, the handle-nuts are removed from the uppermost door 110 12, and the latter is removed from the opening and allowed to swing off to one side by means of the chain 20. The person in charge enters the silo through the opening and throws out the silage and it drops into a wagon or other receptacle which is placed 115 directly below the opening. After the ensilage has been removed to a certain depth, the second door from the top is opened in the same manner, and so on till the silo is emptied. The doors are then left in open position until the next filling up of the silo takes place.

120 Long experience in the use of silos has shown that to prepare and preserve ensilage in the best manner, it is important that it be 125 packed in the silo and allowed to settle evenly as possible, so that the curing may be uniform throughout every part of the tank, and the tanks, including the doors and other movable parts must be made and main- 130

tained air-tight, or else the food will become spoiled. It is important also that the movable parts should be made and disposed in a simple manner, so that they may be handled with the least exertion and as readily as possible. Having these ends in view, and also a desire to increase the strength and lessen the expense of devices of the class, I have devised and constructed my improved silo in the manner herein shown and described, providing a clear and free interior together with the novel and simple means for opening, closing and suspending the discharge doors.

15 It is obvious that changes or modifications may be made in the form and arrangement of some of the parts without departing from the spirit of my invention, and I therefore do not restrict myself to the precise construction and application of the same as herein described and shown.

Having thus described my invention, what I claim as new and desire to secure by Letters Patent, is—

25 1. A silo, comprising a tubular tank, a discharge opening formed through the wall of said tank, the ends and sides thereof being beveled in different directions, a beveled edge door adapted to fit and tightly close said opening, a chain to support said door when open, means for securing the lower end of said door to the wall of said tank, and a pair of looped handles attached to the outer face of said door, substantially as described.

35 2. A silo, comprising a stave-tank having an unobstructed interior, a series of discharge openings formed in one side of said tank arranged one above the other, a movable door adapted to close each of said openings from the outside, a chain to support and

carry each door when in open position, a hasp secured to the lower part of each door, a pair of studs to engage the ends of said hasp, and a pair of handle-nuts to hold each door in closed position, substantially as described. 45

3. A silo, comprising a stave-tank having an unobstructed interior, a series of discharge openings formed in the side of said tank disposed one above the other, a movable door adapted to close each opening from the outside, a hasp secured to the lower part of each door, a pair of studs adapted to engage the ends of said hasp, and a pair of nuts to hold each door in closed position, substantially as described. 55

4. A silo, comprising a circular tank having an unobstructed interior throughout its full length, a series of detachable doors formed by cutting out a portion of the wall of said tank, the said doors being arranged one above the other at equal distance apart and adapted to be inserted in the discharge openings only from the outside of the tank, a chain attached to each door and to said tank 60 by means of which the doors, when open, are suspended on one side and clear of the discharge openings, a double hasp carried by each door, a pair of studs projecting from said tank near the lower end of each door, 70 and a pair of handle-nuts adapted to co-operate with said hasp and said studs for locking and holding said door in closed position, substantially as described. 65

In testimony whereof I affix my signature 75
in presence of two witnesses.

FREDERICK E. HUDSON.
